UNITED STATES PATENT OFFICE.

ARTHUR E. MOLIN, OF STILLMAN VALLEY, ILLINOIS.

AEROPLANE.

Application filed March 22, 1920. Serial No. 367,732.

To all whom it may concern:

Be it known that I, ARTHUR E. MOLIN, a citizen of the United States, residing at Stillman Valley, in the county of Ogle and 5 State of Illinois, have invented certain new and useful Improvements in Aeroplanes, of which the following is a specification.

This invention pertaining in general to aeronautics, has more particular reference to 10 aeroplanes, and especially to the control of lateral stability thereof.

The primary object of my invention is to provide an improved and novel means for 15 operating the auxiliary wing surfaces for the purpose of controlling lateral stability of the plane.

Another important object is the provision of novel means whereby the angle of incidence may be changed at the will of the 20 operator for the purpose of varying the lifting and stabilizing effect of said wing surfaces.

My invention further contemplates the provision of a control means of the character described of much simpler construction than the ordinary wire controls now employed, and adapted to be applied to any 25 aeroplane having auxiliary wing surfaces in the form of flaps, ailerons or auxiliary wing 30 tips such as employed in the present case.

In furtherance of these general objects, I have provided a lever interposed between and pivotally connecting the auxiliary wing surfaces and pivotally mounted medially 35 upon the plane so that when rocked upon its pivotal mounting said wing surfaces at opposite ends of the main wings will be raised and lowered inversely. This lever is connected with the main control member, in 40 the present instance to the control stick, by means of which both lateral and longitudinal stability is maintained. By vertically adjusting the pivotal mounting of said lever the angle of incidence of the auxiliary wing 45 surfaces will be changed.

Other objects and attendant advantages will be appreciated as the invention becomes better understood by reference to the following description when considered in connection with the accompanying drawings, in which—

Figure 1 is a fragmentary diagrammatic view of an aeroplane embodying my improvements;

Fig. 2, a perspective view of one of the auxiliary wing surfaces;

Fig. 3, a fragmentary view looking forward at the lever which connects the auxiliary wing surfaces at the opposite ends of the main wings, and showing the parts immediately connected to said lever;

Fig. 4, a detail side view of the pivotal connection at the lower end of Fig. 3;

Fig. 5, a sectional view taken on the line 5—5 of Fig. 3; and

Figs. 6 and 7, diagrammatic views illustrating different movements of the lever control, which will be explained more fully hereinafter.

My improvements are applicable to any 70 type of aeroplane, that is, irrespective of the number of wings distinguishing such types, and in the present instance are employed in connection with a bi-plane. For purpose of clarity I have illustrated in the drawing 75 only such parts of a plane as are essential for an understanding of my present invention. These parts consist of the main upper and lower wings 11 and 12 respectively connected by suitable struts, and a fuselage, of 80 which only the bottom 13 of the cock pit is shown. A stick control of conventional design is employed comprising the stick 14 pivotally mounted on the horizontal rock 85 shaft 15 to swing forwardly and backwardly thereon, but to rock laterally with said shaft. A transverse rock shaft 16 equipped at its ends with rocker arms 17 connected in the usual manner with the elevator flaps, is adapted to be operated from 90 the stick 14 through the agency of the link connection 18. The foot lever 19 is adapted to operate the rudder in the usual manner.

The auxiliary wing surfaces at or near the 95 ends of the main wings may be of any suitable or preferred shape, proportions or design, and in the present instance are of the same cross-sectional shape and dimensions as the main wings. These auxiliary wing surfaces 21 and 22 at opposite ends of the main wings are each pivotally attached to the latter adjacent to the forward edges thereof, as for example, by being pivotally mounted upon the front spars 23 which are rigid with and extend beyond the main 105 wings. The remaining spars terminate at the outer ends of the main wings, so that the auxiliary wing surfaces 21 and 22 are free to swing vertically upon the front spars 23. Struts 24 connect the upper and lower auxiliary wings at each end of the plane so that 110 each pair will be held in parallel relation at

all times. These struts 24 are joined by a horizontal lever 25 pivotally mounted upon a stud 26 medially between the auxiliary wings. This stud is at present formed integral with a part 27 which threadingly engages and is supported by a vertical screw rod 28 suitably mounted for rotation but held against movement longitudinally of its axis. Connected rigidly with the lever 25 is a depending member 29 telescopingly engaged with a part 31 which is pivotally connected at 32 with an upstanding crank arm 33 rigidly connected to the forward end of the rock shaft 15. By reason of the foregoing construction, it will be manifest that by swinging the stick 14 to the left, that is, in a counter-clockwise direction viewing Fig. 1, the lever 25 will be rocked upon its mounting 26 in a similar direction, thus lowering the auxiliary wings 21 and raising the wings 22 for the purpose of causing the left end of the plane to dip, or for the purpose of maintaining lateral stability as is well known.

For the purpose of varying the angle of incidence of the auxiliary wings, the pivotal mounting of the main lever 25 may be raised or lowered by revolving the screw 28. This may be done in any suitable manner, as by means of a hand crank 34 connected by means of a sprocket chain 35 with the screw shaft 28.

In Figs. 6 and 7, the action is illustrated diagrammatically, showing in the former the tilting of the main lever 25 about its pivot 26, and showing in the latter the pivotal point 26 raised, thereby lowering the angle of incidence.

It is believed that the foregoing conveys a clear understanding of the objects prefaced above, and while I have illustrated and described but a single embodiment of my improvements, it should be understood that various changes might be made in the construction and arrangement without departing from the spirit and scope of the appended claims, in which—

I claim:

1. In an aeroplane, the combination of the main wings, auxiliary wing surfaces for the purpose of lateral stability, a lever pivotally connected at its opposite ends directly with said wing surfaces and pivotally mounted medially of the plane, for tilting said auxiliary wing surfaces with respect to the main wings, and means for raising and lowering the pivotal mounting of said lever with respect to the main wings for the purpose of uniformly changing the angle of incidence of the auxiliary wing surfaces at both ends of the planes.

2. In an aeroplane, means for changing the angle of incidence of the ailerons at the outer ends of a main wing, comprising a lever pivotally mounted medially between the ailerons and reaching laterally and connected substantially directly thereto, and means for raising and lowering said pivotal mounting of the lever whereby to increase or decrease the angle of incidence of both said ailerons.

3. In an aeroplane, the combination of auxiliary wing surfaces for purpose of lateral stability, a member connecting said wing surfaces and pivotally mounted intermediate its ends, vertically adjustable means upon which said member is pivotally mounted, and manually operable means for adjusting said member-supporting means vertically to uniformly change the angle of incidence of both wing surfaces.

4. In an aeroplane, the combination of auxiliary wing surfaces for purpose of lateral stability, a lever connected at its ends with said wing surfaces and adapted to rock medially for changing the angle of incidence of said surfaces inversely, a vertical threaded member, means supporting and threadingly engaging said threaded member, and means for revolving said threaded member for vertically adjusting the pivotal support of said lever.

ARTHUR E. MOLIN.
